UNITED STATES PATENT OFFICE.

OLENDÖ TROMSNESS, OF MINNEAPOLIS, MINNESOTA.

COMPOSITION OF MATTER USED FOR CLEANING GUN-BARRELS.

1,036,383.

Specification of Letters Patent. Patented Aug. 20, 1912.

No Drawing.

Application filed April 17, 1912. Serial No. 691,528.

To all whom it may concern:

Be it known that I, OLENDÖ TROMSNESS, a citizen of the United States, residing at Minneapolis, in the county of Hennepin and 5 State of Minnesota, have invented a new and useful Composition of Matter Used for Cleaning Gun-Barrels, of which the following is a specification.

My composition consists of the following 10 ingredients, combined in the proportions stated, viz: one sixth part acetone, one sixth part amyl acetate, one sixth part turpentine, one half part sperm oil. These ingredients are to be thoroughly mingled by agitation.

15 In using the above named composition the gun barrel is swabbed with the mixture, the gun powder and carbon deposit in the barrel being instantly dissolved by the composition and the swab serving to remove the deposit in the usual manner. My composition 20 is particularly useful for cleaning large and small gun barrels and in practice has been found very desirable to use on military rifle ranges. This composition in addition to 25 acting as a good powder solvent also acts as a rust preventive and a lubricant when applied to the metal parts of a gun barrel and also makes a good polish for gun stocks.

I am aware of patents upon compositions 30 which are adapted for use in removing varnish granted to James Miller on April 7,

1903 No. 725,002; on Dec. 22, 1903 to Thomas Stack, *et al.* No. 747,898; on November 19, 1907 to Toch No. 871,195 and of patents granted on May 20, 1890 to Hand No. 35 428,486 and to Toms on May 28, 1867 No. 64,139 which are adapted for use as washing compounds. The compositions disclosed in these patents however are not adapted to dissolve gun powder and I do not claim as 40 my invention such combinations broadly.

I claim:

1. The herein-described composition of matter adapted for dissolving gun powder in gun barrels, consisting of acetone, amyl 45 acetate, turpentine and sperm oil, substantially as described and for the purpose specified.

2. The herein-described composition of matter for cleaning the barrels of rifles and 50 guns, consisting of acetone one sixth part, amyl acetate one sixth part, turpentine one sixth part and sperm oil one half part, substantially as described.

In testimony whereof, I have signed my 55 name to this specification, in the presence of two subscribing witnesses.

OLENDÖ TROMSNESS.

Witnesses:

G. M. DEEBACH,
I. G. BRADBURY.
